BUILDING BLOCK

Willard P. Zimmerman and Minot K. Holmes,
Muncie, Ind., assignors to Owens-Illinois Glass
Company, a corporation of Ohio

Application May 26, 1936, Serial No. 81,814

5 Claims. (Cl. 72—41)

The present invention relates to improvements in hollow building blocks and walls constructed therefrom. More particularly the invention is concerned with blocks formed of glass or other such vitreous materials.

An object of the invention is the provision of a hollow building block composed of several sections united in such fashion that the parting line between the sections will be disposed between the exposed faces of the block. Thus, the parting line or joint when the blocks are built into a wall structure, will have the benefit of the protection and added strength afforded by the mortar or other medium employed in joining the blocks together and further will not be exposed to view.

Another object is the provision of a hollow glass building block formed by uniting hollow sections with an inorganic bonding medium such for example as aluminum, aluminum silicon alloy or other suitable metal.

Other objects will be in part apparent and in part pointed out hereinafter.

In the drawing:

Fig. 1 is a perspective view of two half block sections prior to assembly.

Fig. 2 is a perspective view showing the block halves assembled.

Fig. 3 is a fragmentary sectional view intended to illustrate the manner in which a portion of the bonding material is absorbed by the glass as the block halves are united.

Fig. 4 is a fragmentary sectional view illustrating a glass-to-glass bond between the block halves.

Fig. 5 is a fragmentary sectional perspective view of a wall made up of blocks of the character shown in Figs. 1 and 2.

This application is a continuation in part of our application, Serial No. 21,095 filed May 13, 1935, now Patent #2,094,287 as to all subject matter common to the two applications.

While the present invention may be embodied in blocks of different shapes and contours, it is for the purpose of illustration identified with a rectangular block made up of two hollow cup-like sections or halves which are intended to be united or joined together in a fashion to form a hermetically sealed chamber therein. To this end the block halves are united as quickly as possible following the molding operation which involves shaping the cup-like halves from molten glass or the like material.

In Figs. 1, 2, and 3 the block is shown as comprising two half sections, each of which includes

parallel longitudinal walls 16 joined together by transverse end walls 17, all of said walls merging at one edge in a bottom wall 15 which constitutes one exposed face of a completed block.

While the two block halves may be united by bringing the edge portions 18 into contact with each other under pressure while still quite hot and in a more or less semiplastic state, as shown in Fig. 4, they may also be united by placing a thin sheet of aluminum foil 19 on the edge of one block half and then properly positioning the other half upon the sheet of foil. When such assembling of the block halves is effected immediately upon completion of the molding operation, the aluminum is quickly melted and operates to effectively fuse the edge portions together. Various other methods of uniting the block halves may be resorted to, such for example as dipping the edge portions into a bath of molten metal in the fashion disclosed in our application identified above.

In Fig. 5 we have shown a fragmentary wall structure made up of blocks constructed as above described. In this wall structure the parting line or joint between the halves of each hollow block is spaced inwardly from the exposed walls 15 or faces and by reason of this location of the joints or parting lines, the mortar 20 serves to further seal the blocks and affords additional protection for the bonding medium employed in uniting the sections of the block. Further, due to the above described positioning of the joints or parting lines, the exposed faces of the wall are unbroken except for the usual mortar lines which are present in all such wall structures and any desired block face decorations.

In view of the above it will be apparent that the present application is intended to cover a wall structure made up of hollow blocks wherein the blocks themselves consist of two or more sections bonded together in such fashion that the joint between the sections is obscured from view. Further it is intended to cover a hollow building block constructed from glass or other vitreous materials and made up of sections (cup-like sections for example) united by an inorganic bonding medium, aluminum, aluminum silicon alloy, copper, etc., and a hollow block made up of sections joined together in such fashion that the joint is spaced inwardly from the exposed faces of the block.

Modifications may be resorted to within the spirit and scope of the appended claims.

We claim:

1. A hollow glass building block comprising a

pair of molded cup-like sections having abutting edge portions and a bonding medium consisting solely of a coating of aluminum applied directly to said edge portions and hermetically sealing the block.

2. A hollow glass building block comprising a pair of molded cup-like sections having abutting edge portions and a bonding medium consisting solely of a coating of aluminum silicon alloy applied directly to said edge portions and hermetically sealing the block.

3. A hollow glass building block comprising sections bonded together, each section including a face adapted to be exposed when built into a wall structure, said faces being disposed opposite each other, and a metallic bonding medium pene-

trating the glass and constituting the sole means for uniting the block sections.

4. A hollow glass building block comprising a pair of molded sections having edge portions intended to be united and a bonding medium consisting solely of a coating of aluminum applied directly to said edge portions and hermetically sealing the block.

5. A wall structure comprising courses of hollow sectional glass blocks and a bonding medium permanently uniting the sections and consisting solely of a coating of aluminum applied directly to the abutting edges of the sections, said edges being spaced inwardly from the exposed faces of the wall.

WILLARD P. ZIMMERMAN.
MINOT K. HOLMES.
